COMBINED LAMP SHADE AND CHAIN THEREFOR

Emmett L. O'Neill, 2515 Chelsea Drive, Oakland, Calif.
94611, and Emmett R. Anderson, 12510 Jolene Court,
Saratoga, Calif.

Filed Apr. 28, 1971, Ser. No. 138,407

Term of patent 14 years

Int. Cl. D26—05

U.S. Cl. D48—16

FIG. 3

FIG. 1

FIG. 2

FIG. 1 is a perspective view of a combined lamp shade and chain therefor showing our new design;

FIG. 2 is a perspective view of the opposite side thereof; and

FIG. 3 is a top plan view thereof.

The chain is fragmentarily shown in FIGS. 1 and 3 for convenience of illustration.

We claim:

The ornamental design for a combined lamp shade and chain therefor, as shown and described.
